Patented Nov. 8, 1921.

UNITED STATES PATENT OFFICE.

AMBROSE FLEMING, OF ALEXANDRIA, VIRGINIA.

ATTACHMENT TO SCREW-FEED PENCILS.

1,396,710.

Specification of Letters Patent. Patented Nov. 8, 1921.

Application filed January 26, 1921. Serial No. 440,116.

To all whom it may concern:

Be it known that I, AMBROSE FLEMING, a citizen of the United States, residing at Alexandria, in the county of Alexandria and 5 State of Virginia, have invented certain new and useful Attachments to Screw - Feed Pencils, of which the following is a specification.

This invention has reference to that type 10 of writing devices in which the pencil holder is designed for containing a number of extra pencil leads adapted for being individually withdrawn, after the closure cap of the holder is removed, for being entered into 15 the lead receiving end of the holder, at which position the lead is frictionally held and adapted for being projected to the writing adjustment, after the writing end of a prior lead is used up, by a plunger pin operated 20 by turning the end cap of the holder.

My invention particularly seeks to provide certain improvements to the type of pencil holder stated that primarily has for its object to hold a relatively large supply 25 of the leads within the casing and in such manner that, under certain adjustments of the lead injector means, a new lead can be instantly and positively fed into position for being engaged by the ejecting devices 30 and projected beyond the point passage of the casing, without the necessity of disconnecting any of the parts of the holder and in which is included a magazine of inexpensive and simple construction that can be 35 easily applied to the casing of a well known type of magazine equipped pencils and used, in addition to the regular leads holding compartment of the pencil, whereby provision is made for carrying a relatively large number 40 of leads in addition to those held in the regular holding compartment of the pencil, and sustained in a position for being individually fed into place to be projected to the writing condition, by a simple manipulation 45 of the parts of the holder without the necessity of separating said parts.

A further object of my present invention is to provide a supplemental leads holding magazine for pencil holders of the character 50 mentioned, that can be readily removed (when emptied) for refilling, by transferring the leads held in the usual way in the holder casing into the said supplemental magazine, the latter when replaced within the holder 55 casing, being adapted for automatically feeding the individual leads into position

for being projected to the writing condition by the plunger pin devices.

Another and essential feature of my present invention is to provide certain improved 60 attachments for the conventional type of pencil lead holders of the kind mentioned, that can be readily embodied in the present construction of magazine equipped pencil without materially increasing their present 65 cost of manufacture, in which the operation of feeding the leads, practically automatically, into the writing position, is so simple that any one familiar with the use of pencil holders such as stated, may manipulate the 70 pencil without danger of breaking the leads or choking the proper co-operation of the connected parts.

With other objects in view that will be hereinafter explained, my present invention 75 comprehends certain improved features of construction and peculiar combination of parts explained in the following detailed description, specifically pointed out in the appended claims and illustrated in the accompanying drawings, in which:—

Figure 1 is a perspective view of a pencil holder embodying my invention, the parts being shown positioned for effecting the operation of feeding a new lead into position 80 to be projected for writing.

Fig. 2 is an enlarged longitudinal section of the pencil casing, with my leads holding and feeding magazine attachments applied thereto, the usual lead projecting means being omitted.

Fig. 3 is an enlarged detail side view of the leads projecting means that coöperate with the parts shown in Fig. 2.

Fig. 4 is a further enlarged detail longitudinal section of a portion of the pencil and the operating portion of the leads projecting device, the latter being shown at the pulled back position indicated in Fig. 1.

Fig. 5 is an enlarged detail cross section 95 taken on the line 5—5 on Fig. 2 and shows the supplemental leads carrying magazine as partially emptied.

Fig. 6 is a similar view taken on the line 6—6 on Fig. 2, the magazine being shown 100 filled with leads.

Fig. 7 is a transverse section, on an enlarged scale, taken on the line 7—7, on Fig. 4, the follower member being shown in elevation and as having been turned out 110 of the pull-back slot.

In the practical development of my pres-

ent invention, instead of making the outer or tapering end of the holder as a fixed part of the casing, it is a separate member, consisting of a body 2 that is formed with a 5 tubular extension 20 whose shouldered end 21 frictionally seats and has rotation within the forward end of the main casing or holder 1 and the inner extremity of the said portion 21 has oppositely disposed longitudinal 10 slots 22, the reason for which will presently appear.

The tubular extension 20 merges with an axial bore 23, which extends through the body 2 and whose outer portion is internally 15 threaded for receiving the steel plug 3 through which the point end of the pencil lead is passed and in which it is gripped against falling out by the longitudinal burs on the sleeves, as is well known to users of 20 the type of pencils mentioned.

The main casing 1 includes the usual inner liner or tube 10 provided with the internal feed screw 11, which extends nearly the full length thereof and with which the 25 screw or follower head 40 engages, the latter being connected to the rear end of the pencil pusher or ejector pin 4, as is best shown in Fig. 3, by reference to which and to Fig. 7 it will be noticed the head 40 is adapted for 30 traveling between the oppositely disposed hollow side bars 42 that constitute the lead holders and which are joined in the usual way, at their outer ends, by an internally threaded head piece 43 onto which the finger 35 cap 5 is secured, it being understood that the head piece 43 has the usual open passages through which the pencil leads, designed α , are fed to assume the position shown in Fig. 7, it being understood that the leads 40 may be readily withdrawn from the said side bars 42, (which bars constitute the primary leads magazine) as hereinafter further mentioned, when the cap 5 is removed.

When the pencil holder is arranged in 45 accordance with my invention, the internal screw way of the liner 10 is cut to produce two opposite channels or grooves 12-12, which extend nearly the full length of the said screw way and, in the inner end of the 50 said liner, is fitted a centrally apertured plug 6, the reason for which will presently appear.

By referring to Fig. 2 of the drawings, it will be noticed the parts are so arranged 55 that a longitudinal chamber is formed by the forward end of the casing 1 and the adjacent tubular end of the rotatable front end or body 2 of the holder, and it is in this chamber, designated 8, in which is 60 mounted the supplemental leads holding magazine, from which, as presently explained, the leads are dropped singly into the leads receiver, from which they are projected forwardly by the ejector pin device, 65 in the usual way.

The pencil lead receiver, in my construction of pencil holder, is a tubular member 9 whose inner end is fixedly fitted within the opening of the plug 6 and whose outer end extends into and loosely engages the inner 70 unthreaded end of the bore of the body member 2.

The tubular member 9 has a slotway 90 that extends the full distance between the plug 6 and the inner end of the tubular portion of the body 2; or in other words, a distance equal or slightly longer than the supplemental leads holding magazine 15 with which it co-operates.

The supplemental magazine 15 is formed 80 by shaping up a thin spring metal blank, substantially the length of the chamber 8 and bending it to tubular form with one edge bent inwardly its full length to produce an internal abutment flange 16 that also constitutes a guide or stop against which that one of the series of leads contained in the said magazine is caused to abut and be held in position for dropping through the slotway 90 of the receiver 9, when the parts are 90 manipulated as hereinafter explained.

It should be stated that, when assembling the parts, the supplemental magazine is dropped into the open end of the casing before the outer end 2 is fitted in place and 95 by holding the said magazine 15 upright, it can be readily filled with leads, arranged in annular relation, as indicated in Fig. 6, it being observed that the leads lie around the tubular receiver 9, which constitutes an 100 inner bearing around which the leads may be rolled, as the magazine is turned to bring that one of the leads, (indicated α in Fig. 6) in position against the stop flange 16 ready for being dropped into the receiver 9. 105

The magazine 15 is provided with a pair of diametrically opposite radial projections 91 that are received within the slots 22 of the tubular extension of the rotatable body 2 of the holder (see Figs. 2 and 5) and by 110 reason of such connection of the magazine 9 and the body 2, rotation of the said body 2, relatively to the casing 1, causes the leads within the magazine to readily come into position for being dropped into the receiver, 115 when the latter is empty.

In the type of pencil holders, for which my attachments are particularly provided, when a pencil lead has been used up, the plunger or ejector pin is slowly withdrawn, 120 by unthreading the parts, and a new lead is supplied by unscrewing the cap 5 on the outer end of the ejector device to permit of withdrawing a single lead, which lead is then inserted through the point aperture in 125 the tapered front end closure of the casings 42.

With my supplemental magazine devices attached, a large number of leads are held within the supplemental magazine and, when 130

they have been used, those in the primary magazines or hollow bars can be readily transferred to the supplemental magazine.

By providing the internal screw way in the liner 10 and forming the said liner with a pair of oppositely disposed longitudinal channels or grooves 12, when it is desired to feed a new lead into place from the supplemental magazine, the ejector pin can be quickly pulled back to the limit of its outward movement, (see Fig. 1) by simply bringing the threaded projection 40 of the plunger head to aline the said grooves 12, since, when thus positioned, the projections are disconnected from the screw way and hence, with the pin, can be almost instantly pulled to the limit of its outward adjustment, which brings the front end of the ejector pin just beyond the inner end of the supplemental magazine (see Fig. 4) and leaves the receiver free for dropping another lead into position, which is done by simply turning the member 2 to bring the next lead *a* in line with the slotway of the pencil receiver.

By then giving the ejector device a turn, the radial projections on the head 40 will at once engage the screw threads and the ejector can then be fed forward in the usual way to feed out the leads, as required.

My improved attachments can be readily applied in connection with the pencil casings and ejector devices of the type of pencils stated without appreciably increasing the expense of manufacture of such types of pencils now on the market.

A great advantage is attained through my invention over the said forms of pencils as now made, since a greater number of leads can be carried in the holder and there is no need of separating any of the parts, when it is desired to place a new lead into position, since all that is necessary is to turn the ejector device in position for being instantly pulled back to the limit of its movement, which insures the proper positioning of the front end of the plunger and leaves the parts in condition for the practically automatic feeding into place of a new lead, a slight turn of the front end of the holder being all that is necessary to accomplish that.

To steady the magazine and provide a solid bearing therefor within the chamber 8, a sleeve 17 is tightly attached thereto and which bears against the inner wall of the tube or casing portion, as shown in Fig. 2.

What I claim is:

1. In a pencil holder of the character described, wherein is provided a casing, a plunger having screw connection with the casing for feeding the lead forwardly and a longitudinally slidable member carrying said plunger and adapted to be turned to feed the plunger forwardly; means for releasing the plunger from feeding engagement with the

casing, whereby the plunger may be withdrawn from coöperation with the leads, a lead magazine, a lead receiver, and means coöperative when the said plunger is withdrawn for dropping leads from the magazine into the receiver.

2. In a pencil holder of the character described, in which is included a casing, a lead receiver within the forward or open end of the casing, a plunger having a screw connection with the casing, whereby said plunger is fed forward for engagement with and to eject the lead within the receiver, the said plunger being adapted for disengagement with the screw connection and freely pulled back from operative connection with the lead receiver, and a leads magazine annularly surrounding the lead receiver and means for sustaining the leads for being dropped into the said receiver by adjustment of the magazine, when the plunger is pulled back.

3. In a pencil holder of the character described, in which is included a casing, a lead receiver within the forward or open end of the casing, a plunger having a screw connection with the casing, whereby said plunger is fed forward for engagement with and to eject the lead within the receiver, the said plunger being adapted for disengagement with the screw connection and freely pulled back from operative connection with the lead receiver, and a leads magazine annularly surrounding the lead receiver and means for sustaining the leads for being dropped into the said receiver by adjustment of the magazine, when the plunger is pulled back, and other means operable externally of the casing for effecting adjustment of the magazine to bring the annularly disposed leads into position for dropping into the receiver and in position for being engaged by the plunger, as it is screw fed in the forward direction.

4. A pencil holder of the character described comprising a casing, a tapered body rotatably mounted in the forward end of the casting, the said body being apertured for the passage of the pencil lead therethrough, the said casing having an internal screw threadway in the rear end thereof, a trough-like lead receiver that extends from the inner end of the threaded portion of the casing into the rotatable body member and in alinement with its lead passage, a plunger device including a head having portions for engaging the screw way in the casing, the said plunger and the threadway being disconnected when the plunger is adjusted to a predetermined position, whereby the said plunger is adapted for being freely pulled directly back to the limit of its movement, whereby to leave the receiver free for the reception of a new lead, a magazine rotatably mounted within the casing

and adapted, when rotated, to feed the leads into the lead receiver, when the latter is empty, and the plunger is drawn back, and connections that join the rotatable casing member and the magazine, whereby rotation of the magazine is effected, when the said casing member is rotated with respect to the receiver.

5. A pencil holder of the character described comprising a casing, a tapered body rotatably mounted in the forward end of the casing, the said body being apertured for the passage of the pencil lead therethrough the said casing having an internal screw threadway in the rear end thereof, a trough-like lead receiver that extends from the inner end of the threaded portion of the casing into the rotatable body member and in alignment with its lead passage; a plunger device including a head having portions for engaging the screw way in the casing, the said plunger and the threadway being disconnected, when the plunger is adjusted to a predetermined position, where-
25 by the said plunger is adapted for being freely pulled directly back to the limit of its movement, whereby to leave the receiver free for the reception of a new lead, a magazine rotatably mounted within the casing
30 and adapted, when rotated, to feed the leads into the lead receiver, when the latter is empty, and the plunger is drawn back, and connections that join the rotatable casing member and the magazine, whereby rota-
35 tion of the magazine is effected, when the said casing member is rotated with respect to the receiver, the said magazine including means for holding the leads in position for dropping their full length into the receiver,
40 when the lead to be dropped is brought into alignment with the open portion of the trough-like receiver and in position for being engaged by the follower device, when the latter is adjusted for engagement with
45 the feed screw in the casing.

6. A pencil holder having a lead passage,

6. A pencil holder having a lead passage,

a trough-like lead receiver in line with the said passage, a plunger coöperative with the casing, said plunger being screw fed to the pencil ejecting direction and freely movable within the casing in the opposite direction, a magazine inclosed within the casing and adapted for holding extra leads in annular relation with respect to the lead receiver, and means operable externally of the holder for turning the magazine with respect to the receiver, whereby to bring a predetermined one of the extra leads in position for being dropped, its full length, into the receiver and in position for being engaged by the screw plunger and ejected through the lead passage in the holder. 50 55 60

7. A pencil holder having a lead passage, a trough-like lead receiver in line with the said passage, a plunger co-operative with the casing, said plunger being screw fed to the pencil ejecting direction and freely movable within the casing in the opposite direction, a magazine inclosed within the casing and adapted for holding extra leads in annular relation with respect to the lead receiver, and means operable externally of the holder for turning the magazine with respect to the receiver, whereby to bring a predetermined one of the extra leads in position for being dropped, its full length, into the receiver and in position for being engaged by the screw fed plunger and ejected through the lead passage in the holder, the said plunger including a head having a radially projected screw thread engaging member, the screw way in the casing having a cut groove extended practically its entire length, whereby, when the thread engaging member of the plunger is turned into alinement with the said groove, the said plunger can be freely withdrawn from the casing to bring its ejecting end in position for being fed out to engage a lead fed from the magazine into the receiver.

AMBROSE FLEMING.
